SHUTTLE EYE ASSEMBLY

Raymond J. Carrigan, Thompsonville, Conn., assignor to Bigelow-Sanford Carpet Company, Inc., Thompsonville, Conn., a corporation of Delaware

Application December 29, 1951, Serial No. 264,019

9 Claims. (Cl. 139—223)

1

The present invention relates to an improved shuttle eye assembly which is adapted for self-threading and for tensioning shuttle thread drawn from the shuttle, and which is particularly adapted for use in a carpet loom of the general type in which the weft yarns are woven in a wet state and under high tension.

It is a principal object of the invention to provide an improved shuttle eye assembly which is particularly adapted for the accurate and efficient handling of wet thread and which will entirely eliminate damaging accumulations of sizing material in the shuttle eye.

It is still another object of the invention to provide for the threading of a new bobbin thread into the shuttle eye and the removal of the old bobbin thread in a novel manner to avoid any possible entanglement of the wet threads which might result in the weaving of the old thread with the new into the fabric.

With these and other objects in view as may hereinafter appear, features of the invention consist in the novel construction and arrangement of the shuttle eye assembly in which the overlying thread engaging hook, the downwardly and rearwardly inclined threading surface of the eye assembly, and the thread tensioning device of the shuttle are located with relation to one another and are constructed and arranged to operate in a novel and improved manner to locate the yarn in the normal feeding position under the control of the thread tensioning device.

Another feature of the invention consists in the further arrangement of the tensioning device and of the thread guiding surfaces associated therewith which are effective to cause the severed thread end when withdrawn in the reverse direction from the shuttle to be disengaged from the tensioning device, and thereby to insure the release and withdrawal of the severed thread end attached to the bobbin discharged from the shuttle eye.

The several features of the invention consist also in the devices, combinations, and arrangement of parts hereinafter described and claimed which, together with the advantages to be obtained thereby, will be readily understood by one skilled in the art from the following description taken in connection with the accompanying drawings, in which

Fig. 1 is a view in side elevation of a shuttle eye assembly through which yarn is being drawn at a tension, the surrounding nose portion of the shuttle being indicated in dotted lines;

Fig. 2 is a plan view of the shuttle eye assembly

2

shown in Fig. 1 with adjacent portions of the shuttle casing shown in dotted lines;

Fig. 3 is an end view looking from the left of the shuttle eye assembly as shown in Fig. 1 again with the surrounding portions of the shuttle casing sectioned and shown in dotted lines; and

Fig. 4 is a fragmentary view of the eye portion of the shuttle eye unit showing the position of the new thread and the old thread at the beginning of the first stroke of the shuttle from left to right following the knocking out of an exhausted bobbin and the placing of a new bobbin in the shuttle.

Referring to the drawings, in which like numbers refer to like parts, the shuttle eye assembly illustrated as embodying in a preferred form the several features of the invention comprises a cast light-weight metal body member 6 which is fitted into a correspondingly-shaped aperture 7 formed in the nose of a shuttle 8 indicated in dotted lines in the drawing. The nose end of the shuttle only is shown and is of conventional shape, being tapered to a point and being provided rearwardly of the nose with a bobbin receiving aperture 9 which houses a bobbin generally indicated at 10. The shuttle is provided along the top surface thereof with a longitudinally extending thread receiving groove 11 and along one side thereof with a thread receiving groove 12 and with a thread opening or aperture 13 having at each side thereof pins 14 around which the feeding thread is drawn from the shuttle, depending upon the direction of shuttle travel. As best shown in Fig. 1, an aperture 15 is provided in the side of the shuttle rearwardly of the thread opening 13, which provides space for the operation of an automatic cutter utilized to sever the thread at the same time that an exhausted bobbin is discharged from the shuttle.

Inasmuch as the mechanism for automatically changing bobbins in the shuttle, including the automatic cutter for severing the thread connected with the discharge bobbin, is well known in the art and forms specifically no part of the invention, no further description or illustration thereof is made herein.

The body member 6 of the shuttle eye assembly is located in the shuttle by means of a post 16 formed on the underside of the body member 6 which engages with a correspondingly formed recess in the bottom of the shuttle. The body member 6 is further held in place by two locking screws, not specifically shown, which are arranged to pass transversely through the shuttle and through two bores 18 in the lower portion of the

body member 6. A deep thread guiding slot 22 is formed in the body member 6 running the length thereof. The body member 6 is roughly rectangular in shape but with the left hand end of the rear wall of the slot, as shown in Figs. 1 and 2, expanded and shaped to form the eye portion of the assembly. At its left hand end this wall is formed with a thread confining hook 24 which is located beyond the end of and overlying the slot 22. The leading edge of the wall provides a downwardly and rearwardly inclined eye threading surface 26 which terminates in a horizontally undercut thread guiding surface 28 lying in substantially the same horizontal plane with the bottom of the slot 22. Between the inclined surface 26 and the adjacent end of the bottom surface of the slot 22 there is provided a thread guiding post 30 which is supported in the expanded portion of the rear wall of the body member 6 and extends depthwise of the slot 22 a substantial distance below the bottom surface thereof. The post supported in this position provides a cylindrically turned surface around which the thread indicated at 31 in Figs. 1, 2, and 3 feeding from the bobbin 10 is drawn through the slot 22 outwardly in a transverse direction through the thread opening 13 in the side of the shuttle during the normal forward and back operation thereof. It will be understood that the invention is not limited to the specific construction shown and that the cylindrically turned surface provided by the post 30 may be formed in any convenient manner.

A tensioning strain is maintained on the thread passing through the shuttle eye and around the post 30 by means of a leaf spring 32 supported on edge along the bottom of the slot 22 and secured by a screw bolt 34 to the inner face of the further wall of the slot. At its left hand end the spring 32 is provided with a cylindrically turned thread engaging surface 36 which is parallel to and bears yieldably against the cylindrically turned surface of the post 30 along a vertical line of contact. The lower edge of the cylindrically turned portion 36 of spring 32, which extends beyond the end of the slot 22, is broadened or flanged downwardly a substantial distance below the bottom surface of the slot 22. A set screw 40 threaded through the rear wall of the body member 6 and held in place by a locking nut 42 is arranged for engagement with the shank of the spring member 32 in order to regulate the tension applied against the thread. The rear wall of the slot 22 is formed at its right hand or thread receiving end with a downwardly and forwardly extending flange 44 which serves to trap the feeding yarn in the slot and thereby maintain its passage horizontally along the bottom of the slot. During the normal operation of the shuttle, the thread 31 as shown in Figs. 1, 2, and 3 travels along the bottom of the slot 22 and around the post 30 adjacent the undercut thread guiding surface 28, being firmly engaged between the parallel contacting cylindrically turned surfaces of the post 30 and thread engaging portion 36 of the tensioning spring 32.

It will readily be appreciated that the arrangement of the self-threading and thread tensioning shuttle eye assembly as thus far described provides an extremely compact simple construction in which all of the operating parts concentrated in the eye portion of the unit cooperate in a most efficient manner for the control of the feeding thread. The construction and relative arrangement of the downwardly inclined end wall

threading surface 26 and of the thread tensioning device supported immediately adjacent thereto consisting of the vertically arranged cylindrical guide surface and associated parallel contacting cylindrically turned spring surface has the specific advantage in a carpet loom where relatively heavy thread tensioning strains are imposed in that the inclined shuttle threading surface 26 acts during the threading operation to exert a powerful downward pull on the thread which causes the thread to be powerfully drawn in a downward direction between the parallel contacting cylindrical surfaces referred to to the normal operating position where the thread is then positively held with relation to the tensioning device by means of the horizontally undercut surface 28 above described. The arrangement of the shuttle eye assembly, including the engaging cylindrical surfaces of the tension device in which these parts are located beyond the end of the thread guiding slot 22, is of advantage also in that very little tendency is encountered for the cylindrical surfaces of the friction device to strip wet sizing material from the feeding yarn or to cause any injurious deposit of such material within the shuttle eye assembly.

Further in accordance with the invention the illustrated shuttle eye unit is constructed and arranged to cause the severed thread end associated with a bobbin being discharged from the shuttle to be moved downwardly so that it is released from engagement between the parallel contacting cylindrical surfaces of the post 30 and spring 32, and may be withdrawn freely from the shuttle eye unit along a path which will avoid any possibility of entanglement with the thread being drawn through the shuttle eye from a newly loaded bobbin on the first stroke or pick of the shuttle from left to right across the loom.

In order to cause the severed thread end to be disengaged from the thread tensioning device and to be withdrawn from the shuttle in the manner described, the near side of the post 30 is cut away to provide a downwardly and rearwardly inclined surface 50. An adjacent portion of the outer side wall of the body member 6 underlying the horizontally undercut guide surface 28 is similarly cut away at 52 to provide a further extension of the rearwardly inclined surface 50. Both of these inclined surfaces 50 and 52 are located slightly below the normal position of the thread 31 during the shuttle operation when thread is being drawn outwardly through the shuttle eye assembly as shown, for example, in Figs. 1, 2, and 3.

However, when the thread leading to the work is severed, and the severed end is withdrawn rearwardly through the shuttle eye assembly upon ejection of the used-up bobbin from the shuttle, the thread end as indicated at 53 in Fig. 4 tends to become somewhat slack and drops into engagement with the surfaces 50, 52, which are thus rendered operative by the rearward pull on the thread from the ejected bobbin to drag that portion of the thread engaging between the parallel contacting cylindrical surfaces of the spring 32 and post 30 downwardly out of the line of contact with these tensioning elements, thus releasing the tension on the thread 53. As further indicated in Fig. 2, the thread end 53 is now positioned in an aperture or passage 54 provided between the cylindrically turned spring portion 36 and the end of slot 22, and will be withdrawn freely and without any further obstruction into

and along the bottom of slot 22 and thence out of the shuttle.

It will be noted that the arrangement of the guiding surfaces 50, 52 is such that these surfaces remain inoperative during normal operation of the shuttle, but are caused to act powerfully and with certainty upon the slack portion of a thread end which is being drawn rearwardly from the shuttle eye assembly to disengage the thread end from the tensioning device so that the thread end may be withdrawn freely from the shuttle. A further advantage of the construction described consists in the fact that the movements of the severed thread end downwardly out of engagement with the spring 15 pressed tensioning device and the subsequent downward movement of the newly threaded bobbin thread from the position indicated at 56 in Fig. 4 into the normal operating position in the tensioning device have a desirable cleansing effect, tending to remove any excessive accumulation of sizing material from the engaging surfaces of the tensioning device, so that a uniform condition of tensioning strain is maintained between the parallel contacting cylindrical engaging surfaces of the tension device.

The operation of the improved shuttle eye unit of the present invention to automatically thread a new bobbin into the machine and to effect the release of the severed thread end from the tensioning device will be briefly described as follows:

When the bobbin in the shuttle is substantially exhausted of filling with the shuttle at the left hand end of its stroke, as viewed for example in Figs. 1 and 2, following a normal procedure, the thread leading from the shuttle eye is severed approximately 5 inches to the right of the eye, the exhausted bobbin is knocked downwardly out of the shuttle, and the new bobbin is substituted from above the shuttle in place of the discarded bobbin. These operations may be performed automatically and without interruption of the continued operation of the loom. The condition of the threads leading from the newly installed bobbin and from the displaced bobbin at the beginning of the first stroke or pick of the shuttle after the change of bobbins has taken place will be as specifically shown in Fig. 4. The thread 58 leading from the newly inserted bobbin passes from the body portion of the shuttle along the upper part of the slot 22 and beneath the hook 24. The severed end of the thread designated at 58 leading from the discharged bobbin lies in a slack position passing around the post 30 and along the bottom of the slot 22. The thread 58 is about to be drawn rearwardly out of the shuttle during continued movement of the shuttle along its line of travel from left to right. As the severed thread end 58 is withdrawn, this thread, being somewhat slack, will engage against the inclined surfaces 50, 52, thus causing the thread to be urged downwardly on the post 30 until it is moved out of engagement with the cooperating cylindrically turned thread engaging portion 36 of spring 32. The thread 58 will now have the position illustrated specifically in Fig. 4 passing beneath the line of contact between the cylindrical post 30 and a cylindrically turned portion 36 of spring 32 and thence passing upwardly through an aperture generally indicated at 54 in Fig. 2 bounded by the noncontacting portions of the cylindrical post 30 and cooperating cylindrically turned portion 36 of spring 32 and by the end of the slot 22. The thread 58, guided in this manner, is now drawn rearwardly

75 without hindrance through the aperture 54 along the bottom of the slot 22 until the thread end is entirely discharged from the shuttle.

During the initial stroke or pick of the shuttle from left to right, the thread 58 from the newly inserted bobbin will ride in the upper portion of the slot 22, feeding outwardly over the nose of the shuttle through the hook 24 and groove 12. Upon the return stroke of the shuttle from right to left, the thread 58 will be drawn relatively to the right down the inclined eye threading surface 26 so that this thread is drawn downwardly at a sharp angle between the cylindrically turned surface 36 of the tensioning spring 32 and post 30 to the normal running position indicated for thread 31 in Figs. 1, 2, and 3.

The invention having been described, what is claimed is:

1. A shuttle eye assembly which comprises a body member having a thread receiving slot along its length including a bottom surface and side walls, one of said side walls having an end thereof shaped to provide a thread confining hook disposed beyond the end of and overlying the slot, an eye threading end wall surface inclined downwardly and rearwardly from said hook for threading the shuttle eye assembly, an undercut thread guiding surface forming a continuation of said inclined threading surface lying substantially in the same plane with the bottom of the slot, and a cylindrically turned surface having its axis depthwise of the slot formed in said wall at the end of the slot and adjacent said undercut surface and extending from above below the bottom surface of the slot for guiding thread transversely from the slot around said cylindrical surface and beneath said undercut surface and having a downwardly and rearwardly inclined bevel surface on that portion extending below said adjacent undercut surface for guiding the severed thread downwardly from said undercut surface, and a thread tensioning device acting on the feeding thread.

2. A self-threading thread tensioning shuttle eye assembly which comprises a body member having a thread receiving slot along its length including side walls, and a bottom thread guiding surface, an eye threading surface formed in one of said side walls inclined rearwardly and downwardly toward the bottom of said slot, an undercut thread guiding surface forming a continuation of said threading surface lying substantially in the same plane with the bottom of the slot, a cylindrically turned guide surface forming a portion of the side wall having said threading and undercut surfaces with its axis depthwise of the slot adjacent said undercut surface and extending from above below the bottom surface of the slot for guiding thread from the slot transversely under said undercut surface, a thread tensioning element having a position of line contact with said cylindrically turned surface along the axis thereof within the slot from above substantially below the level of the slot, said body member having below the level of the slot and laterally of said cylindrically turned surface a rearwardly and downwardly inclined thread engaging surface for engagement with the severed end of a thread drawn rearwardly through said eye assembly to disengage said thread beneath the tensioning element.

3. A shuttle eye assembly which comprises a body member having a thread receiving slot along its length including a bottom surface and side walls, one of said side walls having an end thereof shaped to provide a thread confining hook

disposed beyond the end of and overlying the slot, an eye threading end wall surface inclined downwardly and rearwardly from said hook for threading the shuttle eye assembly, an undercut thread guiding surface forming a continuation of said inclined threading surface lying substantially in the same plane with the bottom of the slot, a cylindrically turned surface having its axis depthwise of the slot formed in said wall at the end of the slot and adjacent said undercut surface and extending from above below the bottom surface of the slot for guiding thread from the slot around said cylindrical surface and laterally beneath said undercut surface, and a cylindrically turned thread tensioning element yieldably supported from the body member in parallel relation to and having a position of line contact with said cylindrically turned surface extending from above below the bottom of the slot.

4. A self-threading thread tensioning shuttle eye assembly which comprises a body member having a thread receiving slot along its length with side walls and a bottom thread guiding surface, one of said side walls having an end thereof shaped to provide a thread confining hook disposed beyond the end of and overlying the slot, an eye threading end wall surface downwardly and rearwardly inclined from said hook for threading the shuttle eye assembly, an undercut thread guiding surface forming a continuation of said inclined threading surface lying substantially in the same plane with the bottom of the slot, and a post providing a cylindrically turned thread guiding surface with its axis depthwise of the slot in said wall adjacent said undercut thread guiding surface at the end of the thread guiding bottom surface of the slot and extending from above below the bottom surface of the slot for guiding thread laterally from the slot against said undercut surface, and a thread tensioning device comprising a leaf spring mounted in said body member having a cylindrically turned thread engaging surface parallel with and in yielding line contact with said cylindrical guiding surface from above extending below the level of said undercut surface.

5. A self-threading thread tensioning shuttle eye assembly which comprises a body member having a thread receiving slot along its length including side walls and a bottom thread guiding surface, an eye threading surface formed in one of said side walls inclined rearwardly and downwardly toward the bottom of said slot, an undercut thread guiding surface forming a continuation of said threading surface lying substantially in the same plane with the bottom of the slot, a cylindrically turned guide surface in the side wall having said threading and undercut surfaces adjacent said undercut surface with its axis depthwise of the slot and extending from above below the bottom surface of the slot for guiding thread from the slot transversely under said undercut surface, a cylindrically turned thread tensioning element yieldably supported from the body member in parallel relation to and having a line contact with a portion of said cylindrically turned surface within the slot extending from above below the bottom of the slot, and a rearwardly inclined thread engaging surface along said wall below said transverse undercut surface at that side of the line of spring contact remote from the slot to engage with and urge below said line of spring contact a slack portion of thread withdrawn around said cylindrical surface through the slot.

6. A self-threading thread tensioning shuttle eye assembly which comprises a body member having a thread receiving slot along its length including side walls and a bottom thread guiding surface, one of said side walls having an end thereof shaped to provide a thread confining hook disposed beyond the end of and overlying the slot, an eye threading surface formed in one of said side walls inclined rearwardly and downwardly toward the bottom of said slot, an undercut thread guiding surface forming a continuation of said threading surface lying substantially in the same plane with the bottom of the slot, a post providing a cylindrically turned thread guiding surface with its axis depthwise of the slot in said wall and extending from above below the bottom surface of the slot for guiding thread from the slot transversely under said undercut surface, a cylindrically turned thread tensioning element yieldably supported from the body member in parallel relation to and having a position of line contact with said cylindrically turned surface within the slot extending from above below the bottom of the slot and providing a free passage for thread past said tensioning element into the slot from beneath and beyond the position of line contact, said post having a downwardly and rearwardly inclined slack thread engaging surface formed in a portion of the post at that side of said line contact remote from the slot and below the level of the undercut surface to engage with and urge slack thread drawn rearwardly around the post and through the slot downwardly beneath said position of line contact.

7. A self-threading thread tensioning shuttle eye assembly which comprises a body member having a thread receiving slot along its length with side walls, and a bottom thread guiding surface, one of said side walls having an end thereof shaped to provide a thread confining hook disposed beyond the end of and overlying the slot, an eye threading end wall surface downwardly and rearwardly inclined from said hook for threading the shuttle eye assembly, an undercut thread guiding surface forming a continuation of said inclined surface lying substantially in the same plane with the bottom of the slot, and a cylindrically turned guide surface with its axis depthwise of the slot formed in said side wall adjacent said undercut surface at the end of the slot extending from above substantially below the bottom surface of the slot, a rearwardly and downwardly inclined thread engaging surface in the outer face of said wall below said undercut surface adapted to be engaged by the severed end of thread being drawn rearwardly through said eye assembly, and a thread tensioning device comprising a spring element mounted in said body member having a cylindrically turned thread engaging surface parallel to and having a position of line contact with said cylindrical surface extending from above below the level of the bottom surface of said slot.

8. A self-threading thread tensioning shuttle eye assembly which comprises a body member having a thread receiving slot along its length with side walls, and a bottom thread guiding surface, one of said side walls having an end thereof expanded transversely from the slot and shaped to provide a thread confining hook disposed beyond the end of and overlying the slot, an eye threading end wall surface downwardly and rearwardly inclined from said hook for threading the shuttle eye assembly, an undercut thread guiding surface forming a continuation of said inclined

threading surface lying substantially in the same plane with the bottom of the slot, and a cylindrically shaped thread guiding surface with its axis depthwise of the slot formed in the expanded portion of said wall adjacent the inclined surface at the end of the slot extending from above substantially below the level of the bottom of the slot for guiding thread from the slot transversely under said undercut surface, and a downwardly and rearwardly inclined thread engaging surface formed in said expanded eye portion of the wall disposed below the level of the bottom of the slot and said undercut surface, a leaf spring supported from the other wall of said slot extending edgewise along the bottom thereof and having a cylindrically turned thread engaging surface parallel to and having a position of yieldable line contact with said cylindrically turned surface from above below the level of the bottom of the slot, and a spring adjusting screw mounted in the body member for engagement with the leaf spring for adjusting the tension thereof against the cylindrical surface.

9. A self-threading thread tensioning shuttle eye assembly which comprises a body member having a thread receiving slot along its length with side walls and a bottom thread guiding surface, one of said walls having an eye threading surface forming the end of said side wall inclined rearwardly and downwardly toward the bottom of the slot, an under-cut thread guiding surface forming a continuation of said threading surface lying substantially in the same plane with the bottom of the slot, a cylindrically turned guide surface forming a portion of said side wall with
